NAPKIN HOLDER

James Edward Stewart, Islington, Ontario, Canada, assignor to J & G Productions Limited

Filed Mar. 5, 1973, Ser. No. 338,357

Term of patent 14 years

Int. Cl. D7—06

U.S. Cl. D7—72

FIG.1

FIG. 1 is a top front perspective view of a napkin holder showing my new design;

FIG. 2 is an elevational view of the side opposite that shown in FIG. 1;

FIG. 3 is a rear elevational view; and

FIG. 4 is a top plan view.

The bottom is substantially plain and unornamented except for the feet shown in the views on the drawing.

I claim:

The ornamental design for a napkin holder, as shown and described.
